United States Patent Office

Des. 180,914
Patented Sept. 3, 1957

180,914

ANIMAL APPARATUS

Robert M. Otis, Encino, Calif., assignor to Continental Cage Corporation, Culver City, Calif., a corporation of California

Application March 12, 1956, Serial No. 40,535

Term of patent 14 years

(Cl. D31—2)

FIG. 1.

FIG. 2.

Fig. 1 is a front view showing the animal apparatus embodying the features of my design, being a perspective view taken from the top and one end of the apparatus. Fig. 2 is an enlarged view of the animal apparatus shown in Fig. 1 taken from the other end thereof.

I claim:

The ornamental design for an animal apparatus, as shown and described.
